CLAIM

The ornamental design for the sleeve for bat with integrated knob as shown and described.

DESCRIPTION

FIG. 1 is a perspective view of a first embodiment of a sleeve for bat with integrated knob;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof;

FIG. 8 is a cross section thereof taken in the plane of line 8-8 of FIG. 6;

FIG. 9 is a perspective view of a second embodiment of a sleeve for bat with integrated knob;

FIG. 10 is a front view thereof;

FIG. 11 is a right side view thereof;

FIG. 12 is a left side view thereof;

FIG. 13 is a rear view thereof;

FIG. 14 is a top view thereof;

FIG. 15 is a bottom view thereof; and,

FIG. 16 is a cross section thereof taken in the plane of line 16-16 of FIG. 14.
